UNITED STATES PATENT OFFICE.

MILTON S. DUNKELBERGER, OF DAYTON, OHIO.

DESIGN FOR A COMBINED FISHING POLE AND REEL.

59,204.

Specification for Design.

Patented Oct. 4, 1921.

Application filed April 28, 1921. Serial No. 465,224. Term of patent 14 years.

To all whom it may concern:

Be it known that I, MILTON S. DUNKELBERGER, a citizen of the United States, residing at Dayton, in the county of Montgomery and State of Ohio, have invented a new, original, and ornamental Design for a Combined Fishing Pole and Reel, of which the following is a specification, reference being had to the accompanying drawing, forming part hereof.

The figure is a perspective view of a combined fishing-pole and reel, showing my new design.

I claim:

The ornamental design for a combined fishing-pole and reel, as shown.

MILTON S. DUNKELBERGER.

Witnesses:

HOWARD S. SMITH,
WILLIAM B. HORMELL.
